Patented December 29, 1903.

UNITED STATES PATENT OFFICE.

HELEN F. AVERY, OF NEW YORK, N. Y., ASSIGNOR TO THE WILL & BAUMER COMPANY, OF SYRACUSE, NEW YORK, A CORPORATION OF NEW YORK.

DESIGN FOR A LAMP-SHADE.

SPECIFICATION forming part of Design No. 36,714, dated December 29, 1903.

Application filed September 19, 1903. Serial No. 173,901. Term of patent 3½ years.

To all whom it may concern:

Be it known that I, HELEN F. AVERY, a citizen of the United States, residing in the city of New York, county of New York, and State of New York, have invented a new, original, and ornamental Design for Lamp-Shades, reference being had to the accompanying drawings, in which—

Figure 1 is a top plan view thereof. Fig. 2 is a side view thereof.

What I claim is—

The ornamental design for a lamp-shade, as shown.

In witness whereof I have hereunto set my hand on this 10th day of September, 1903. 15

HELEN F. AVERY.
